WILLIAM B. WILEY, OF MOUNT CLEMENS, MICHIGAN, ASSIGNOR TO CLARE L. BRACKETT, OF DETROIT, MICHIGAN.

PROCESS OF FORMING COMPOSITE SCREWS OR BOLTS.

Application filed June 30, 1924. Serial No. 723,211.

This invention relates to an improved process for correlating a relatively hard insert or slug with a bolt head whose component metal is of considerably less hardness, and has for its object the production of such an article, as for example a tappet bolt, in whose longitudinally bored top end such a slug has been placed at the commencement of the operation about to be described. Its special value lies in the firmness, amounting to structural integrity, which characterizes a tappet bolt thus built up. It further obviates the necessity of resorting to the special hardening of the tappet end surface of the bolt, so that it will function adequately in that exacting capacity, while leaving the threaded stem portion untreated, though of ample hardness to meet all structural and service needs. Experience has shown this special and localized hardening to be at best a very expensive and intricate operation, whose most careful and scrupulous performance still leaves a high percentage of rejections of the completed articles to be expected.

In the drawings:

Figure 1 is a sectional elevational view of the bolt and its inserted slug in position of first assemblage relatively to the die and punch member.

Figure 2 is a similar sectional elevation showing the punch member descending upon the slug with the resultant seating of the slug in the bottom of the bore as well as the initial movement of the bolt through the die.

Figure 3 shows the next step in the process, with the bolt well on its way through the die.

Figure 4 shows the bolt with its head still in the die but so far advanced therethrough that the compression action on the head is about completed.

Figure 5 is an elevational view of a completed bolt with the position of the hard slug indicated in dotted lines.

In carrying out my invention, I provide a die member A, whose forming aperture B is of very slightly less diameter, at the most a few thousandths of an inch, than the diameter of the head D of the stem member C. In the head D there has been previously bored a pocket or depression F, into which the hard metal slug E has been placed. As

will be observed from inspection of Figures 1 and 2 particularly, the sides of the bore F are preferably very slightly inclined, so that so far as manual insertion of the slug E is concerned, it can not be pushed clear to the bottom of the depression. With these parts positioned as thus described and as illustrated in Figure 1, the slug E is subjected to the very forcible impact of the punch G; part of the effect of this stroke is to drive the slug E farther into the bore F, but a very appreciable proportion of its driving force is communicated to the body of the bolt C, to effect its lengthwise or downward movement through the aperture B of the die A. In view of the die's smaller diametrical size above remarked upon, this can only take place resultant upon the corresponding centripetal yielding of the relatively soft head D, whose only outlet or compensatory space is the very slight spaced or tapering character of the bore F as contrasted with the inserted slug E. This results in so firmly or intimately associating the soft metal sides of the bore F with the sides of the inserted slug E, that when the bolt emerges from the die the slug is structurally integral therewith. Of course the impact of the die G on the slug and its tappet head is of such exceedingly momentary duration that a high rate of production can be easily attained, but in so far as the various forming steps in its path of travel can be illustrated, Figures 1, 2, 3 and 4 show successive steps in this operation.

What I claim is:

1. The process of securing a relatively hard slug in the hollowed-out central portion of the top of a bolt of relatively soft metal, consisting in subjecting the slug when positioned therein to longitudinally applied impact coincidently with, and to resultantly effect, the passage of the head of the bolt through a die passage of slightly less diameter, thereby effecting an inward flowing of the component metal thereof into holding engagement of the slug by the sides of its central bore.

2. The process of effecting the structural correlation of a relatively hard slug in a terminally positioned recess in a bolt head of markedly greater external diameter and whose component metal is relatively softer, consisting in positioning the bolt head with

its loosely inserted slug in a die having a bottomless bore of very slightly smaller diameter than that of the bolt head, and effecting the driving of the same completely there-
5 through by impact of a coaxially moving die element upon the exposed top of the slug, thereby effecting a centripetally flowed

movement of the relatively soft metal of the bolt head into positive holding engagement with the sides of the initially loosely positioned slug. 10

In testimony whereof, I sign this specification.

WILLIAM R. WILEY.
